Application November 21, 1929, Serial No. 408,685

10 Claims. (Cl. 226—26)

This invention relates in general to bottle filling machinery such as is used for filling bottles with carbonated beverages and more particularly to machinery of this class adapted to supply or fill the bottle with several ingredients as, for example, with a small supply of concentrated sirup and with sufficient carbonated water to completely fill the bottle. Many beverages now on the market are made up of a certain proportion of concentrated sirup and carbonated water. It is important that the sirup and carbonated water be supplied to the bottles in proper proportions in order to make the beverage tasty and wholesome although the proportions of sirup and carbonated water vary for various beverages.

In a well known type of automatic bottle filling machinery a rotatable enclosed liquid receptacle is provided and carries a number of filling heads and also a number of bottle holders, the latter being automatically raised and lowered first to bring the bottles into cooperative relation to the filling heads for filling and to then move them away from the filling heads as the bodily rotation of the bottle holders with the liquid receptacle carries them to the discharge means or turn-out chute associated with the machine. When the bottles are brought to the filler head they are first filled with the gas under pressure until the pressure in the bottle is the same as the pressure on the carbonated liquid in the receptacle. The carbonated liquid is then delivered into the gas filled bottle with the result that all foaming and loss of liquid is avoided.

One of the principal objects of the present invention is to provide, in a machine of this character, for the delivery to the bottle of a measured amount of sirup and to co-ordinate the delivery of the sirup and the handling thereof with the automatic operations incident to the filling of the bottle with gas pressure and with the carbonated liquid or carbonated water.

Another object resides in the provision of a machine of this character and having these advantages and capacities and which is simple and durable in construction, reliable and effective in operation, and easy and comparatively inexpensive to manufacture.

A further object is to provide a machine of this character wherein the amount of sirup delivered to each bottle may be readily varied.

Other objects and advantages reside in certain novel features of the construction, arrangement and combination of parts which will be herein-after more fully described and particularly pointed out in the appended claims, reference

being had to the accompanying drawings, forming a part of this specification, and in which:

Figure 1 is a fragmentary view partly in side elevation and partly in diametrical vertical section, illustrating an automatic bottle filling machine embodying the present invention;

Figure 2 is a fragmentary sectional view of one of the filling heads similar to Figure 1 but on an enlarged scale;

Figure 3 is a view in transverse vertical section taken in the plane of line 3—3 of Figure 2 and looking in the direction of the arrows on the left hand side of the plane of section;

Figure 4 is a view similar to Figure 3 but looking in the direction of the arrows on the right hand side of the plane of section;

Figure 5 is a view in section taken on line 5—5 of Figure 2;

Figure 6 is a sectional view taken on line 6—6 of Figure 2;

Figure 7 is a view in section taken on line 7—7 of Figure 2;

Figure 8 is a fragmentary detail view partly in side elevation and partly in transverse vertical section and showing a modified form of adjustable stop for the diaphragm of the measuring chamber; and

Figure 9 is a view in horizontal section taken on line 9—9 of Figure 2.

Referring to the drawings, it will be seen that there is shown an automatic bottle filling machine of the type fully shown and described in Patent No. 1,166,520, granted January 4, 1916, to John E. Henes. This type of bottle filling machine has an hermetically sealed receptacle 1, in the lower portion of which a quantity of liquid is maintained at a constant level. Above the liquid and within the receptacle 1 a supply of gas under pressure is maintained. For these features and for the manner of supporting and automatically raising and lowering the bottle holders 2, reference is made to the patent referred to above, which contains a full disclosure of these features.

For the purpose of the present invention, it is sufficient to understand that the receptacle 1 is supported for rotation and is constantly rotated under the action of a suitable power drive. The bottle holders 2 are constrained to rotate with the receptacle and are raised and lowered by individual fluid pressure motors, each having a control valve regulated in its action automatically by means of fixed pins or rollers positioned to open and close the valves at the proper time. The parts are arranged to ele-

vate the bottle holders just after they have passed the loading station and to lower the bottle holders before they reach the discharge station or turn-out chute.

5 As in the patent above referred to, the receptacle 1 is provided around its periphery with a number of filling heads designated generally at 5. The construction of these filling heads differs in some respects from that of the filling heads in the patent above mentioned in order to adapt them to dispense sirup as well as carbonated water and to dispense the sirup in measured quantities. Each filling head 5 has a body 6 coupled or connected as at 7 to the liquid receptacle 1. A filling siphon is provided on each filling head and has a long bottle filling leg 8 in the form of a tube, the lower end of which is provided with a collar 9 formed with a valve seat and the upper end of which is threadededly 10 connected with the body of the filling head and in free and open communication with a liquid supply passage 10. The inner end of this passage 10 is connected to the angularly formed short leg 11 of the siphon, the lower end of 15 this short leg 11 being immersed in the liquid in the receptacle 1. A valve 12 is arranged to coact with the seat on the collar 9 (see Figure 2), and is carried at the lower end of an elongated stem 13, much smaller in cross section 20 than the bore of the tube 8 and adjustably connected at its upper end to the center of a diaphragm or pressure responsive member 14, the periphery of which is held against an annular seat or shoulder 15 in a pressure chamber 16 25 by means of a ring nut 17. Below the diaphragm 14 the chamber 16 is in open communication with the liquid supply passage 10 by virtue of the provision of an axial opening or passage 10' provided in the body of the filling head and connecting the passage 10 with the lower portion 30 of the chamber 16 and with the upper end of the filling tube 8 of the siphon. Since the liquid in the receptacle 1 is under pressure and since the diaphragm 14 is subjected to the action 35 of this liquid under pressure and flexed upwardly thereby, the valve 12 is normally closed.

40 A bottle sealing cap, designated generally at 20, is slidably fitted on the filling tube 8 of the siphon although prevented from falling off of the tube by the collar 9. A gasket or sealing ring 21 is embodied in this cap 20 and is engageable with the upper end of the bottle as 45 shown in Figures 1 and 2 to provide a seal between the cap and the bottle. For the purpose of providing a seal between the cap 20 and the filling head, when the cap is in its raised position, the portion of the filling head surrounding the upper end of the filling tube 8 is provided with a gasket or sealing ring 22 with which a neck 20' of the sealing cap engages.

50 The initial operation in filling the bottle consists in building up pressure therein until the pressure in the bottle equals the pressure acting on the liquid in the receptacle 1 and the means employed for carrying out this purpose 55 includes a pressure supply passage 25 leading horizontally through the filling head, the inner end of the passage 25 being in open communication with the interior of the receptacle 1 and the outer end of the passage 25 terminating at a 60 valve seat 26 formed on the outer end portion of the filling head. A pressure transfer passage 27 is also provided through the filling head and extends from the face of the valve seat 26 inwardly and downwardly through the filling head

65 to a series of passages 28 located within the gasket ring 22 and adapted to discharge pressure down through the sealing cap 20 and into the bottle. The points at which the passages 25 and 27 extend through the valve seat 26 are spaced from 70 each other as shown in Figure 4 and their communication is regulated by a disc valve 29 supported at its center for rotary movement on the filling head by means of a pivot bolt 30 and urged against the seat 26 by a spring 31 encircling the outer end of the bolt. A nut 32 is threaded on the outer end of the bolt and engages the outer end of the spring to tension the same properly. An anti-friction device 34 may be interposed 75 between the inner end of the spring 31 and the adjacent portion of the valve 29. The inner face of the disc valve 29 is recessed to receive a washer 35 and both the valve and washer 35 have diametrically opposite arcuate slots designated at 37 and 38. Except for the slots 37 and 80 38 the washer 35 is imperforate. The slot 38 of the valve is designed to form a bridge or connection between the passages 25 and 27 in one position of the valve so that pressure may be carried from the pressure supply passage 25 to the 85 pressure transfer passage 27. In another position of the valve the slot 38 similarly connects the transfer passage 27 with a vent 39 leading from the surface of the valve seat 26 to the atmosphere. The valve 29 is automatically shifted 90 by means of cams 40 and 41 provided thereon and respectively and successively cooperable with pins or rollers 42 and 43 carried by the fixed structure of the machine or by stationary posts 44 mounted adjacent the machine. The 95 posts 44 and the pins carried thereby are so positioned as to operate the valves of the filling heads at the proper time in the cycle of the operation.

100 After a bottle holder 2 elevates a bottle to the 115 position shown in Figures 1 and 2, wherein a seal is provided between the cap 20 and the bottle and between the cap 20 and the filling head, the valve 29 is shifted to the position in which the slot 39 connects or bridges the passages 25 120 and 27. As a consequence, the pressure in the 125 interior of the receptacle 1 above the liquid flows through the passage 25, across the slot 38 and down through the passages 27 and 28 and through the opening of the cap 20 into the interior of the 130 bottle. When the pressure in the interior of the bottle has reached the same value as the pressure in the receptacle 1 above the liquid it is 135 desirable to open the valve 12 so that the liquid in the receptacle will be siphoned into the bottle. For this purpose the pressure transfer passage 27 connects with a branch passage 45 which extends up through the filling head and through the passage of a connecting member 46 and leads into the interior of the pressure chamber 16 140 above the diaphragm 14 thereof. As a consequence of this arrangement, when the pressure is building up in the bottle it is building up in the chamber 16 above the diaphragm 14 and when the pressure in the chamber 16 rises to 145 the same value as the pressure in the receptacle 1, the pressures on the opposite sides of the diaphragm 14 are balanced and the weight of the valve 12 and its stem 13 as well as the weight of the diaphragm causes the diaphragm to flex 150 downwardly and consequently results in the valve 12 moving downwardly away from the seat of the collar 9 thereby permitting the liquid to flow through the siphon and into the bottle. This flow continues until the level of liquid in the bot-

tle rises to the level of the liquid in the receptacle 1. These levels are so regulated as to fill the bottle to the desired extent. The operations are so timed that shortly after the bottle is completely filled the valve 29 is shifted by virtue of the engagement of its cam 41 with a roller or pin 43 to bring a blank or imperforate portion of the valve over the pressure supply passage 25 and bring the slot 38 in bridging or connecting relation to the pressure transfer passage 27 and vent 39. When the valve is so positioned the pressure above the diaphragm 14 is exhausted and consequently the pressure below the diaphragm flexes it upwardly and closes the valve thereby preventing flow of the liquid when the bottle is lowered away from the filling head.

With the present invention it is proposed to deliver into the bottle a measured amount of sirup or other liquid simultaneously with the filling of the bottle with the carbonated water. To effect this result the connecting member 46 is screwed or otherwise fastened to the filling head and has liquid and gas tight connection therewith by virtue of the interpositioning between the coupling and the filling head of a washer or gasket 47. Above the connecting member, a sirup measuring chamber 48 is disposed and is secured in position by a conventional type of coupling 50 swiveled on the connecting member 46 and having the conventional mutilated or arcuate flanges 51 cooperable with the usual tapered mutilated flanges 52 on the lower end of the measuring chamber 48 so that upon appropriate manipulation of the coupling member 50, the measuring chamber will be forced into fluid tight connection with the connecting member 46, this fluid tight connection being established by means of a gasket 53 interposed between the measuring chamber and the connecting member. A diaphragm or pressure responsive member 55 is clamped between the upper end of the measuring chamber and a pressure cylinder 56 secured to the measuring chamber by means of screws 57 or other suitable fastening means.

Sirup is supplied from any suitable source, such as an elevated supply tank (not shown), through a sirup supply pipe 60 (see Figure 1), the supply pipe 60 connecting through a swivel coupling 61 with a pipe 62 extending down through a stuffing box 62' provided on the top of the rotary receptacle 1 and connected to a supply manifold 63 positioned within the receptacle. Branch pipes 64 lead from the manifold 63 to each filling head, each branch pipe being connected with a sirup supply passage 65 formed in and extending lengthwise of its filling head. Each sirup supply passage 65 terminates at the surface of the valve seat 26 as shown in Figure 4 and in spaced relation to a sirup transfer passage 66 also leading from the surface of the valve seat 26 and extending through the filling head to a passage 67 in the connecting member 46, the passage 67 discharging into the open lower end of the measuring chamber. The passages 66 and 67 are in effect a single continuous passage serving both as an inlet and discharge passage for the measuring chamber. A sirup discharge or delivery passage 68 leads from the surface of the valve seat 26 at an angle through the filling head and communicates through the passage 10' at a point just above the filling tube 8. The arcuate slot 37 of the valve 29 operates in one position of the valve to bridge or connect the sirup supply passage 65 and sirup transfer passage 66 thereby supplying the sirup to the measuring chamber 48. In the

other position of the valve the supply passage 65 is blocked and the slot 37 bridges or connects the transfer passage 66 with the discharge passage 68 thereby permitting the sirup to flow from the measuring chamber through the passages 67, 66 and slot 37 to the discharge passage 68 and thence through the filling leg 8 into the bottle.

In order to determine or measure the amount of sirup dispensed into each bottle the diaphragm 55 has a pin 70 secured to the center of a cup 71 which is also fastened to the upper face of the diaphragm at its center. The pin 70 is slidably fitted in an axial bore or opening formed in an adjustable stop sleeve 72, the sleeve 72 being slidably and rotatably fitted in a guide 73 provided therefor in the upper end of the cylinder 56. A stuffing box 74 is provided between the lower end of the guide 73 and the stop sleeve 72. The periphery of the sleeve 72 is formed with a series of recesses or blind holes 75 arranged spirally around and along the stop sleeve and adapted to selectively cooperate with a spring projected pin or detent 76 mounted on the cylinder 56 and projectable across the opening of the guide 73 and into engagement or interfitting relation with any one of the recesses 75 that may be aligned therewith. The spiral arrangement of the recesses 75 about the sleeve 72 is such that for any angular adjustment of the sleeve only one of the recesses 75 is in vertical alignment with the pin 76 and consequently the pin 76 will snap into only one of these recesses. For turning the sleeve 72 while permitting it to slide freely through its guide 73 until one of its recesses is engaged with the pin 76, a flanged collar 77 is rotatably supported on the reduced upper end of the cylinder 56 and is constrained to rotary movement by means of set screws 78 threaded through the collar and having plane or smooth inner ends fitted in an annular groove formed in the reduced upper end of the cylinder. Integral with the collar 77 is an inwardly projecting fin or key 79 which is slidably fitted in a lengthwise groove 80 formed in the sleeve. By turning the collar 77 or the sleeve 72 connected thereto, any one of the recesses 75 may be brought into vertical alignment with the pin 76. As the recesses 75 are not only angularly spaced around the sleeve 72 but also spaced axially therealong, they, together with the pin 76, provide means for releasably locking the stop sleeve 72 in various adjustments with respect to the diaphragm and consequently determine the limit of upward flexure of the diaphragm.

The volume of the measuring chamber depends upon the amount of the upward flexure of the diaphragm and this in turn is determined by the position of the stop 72 which engages a boss 71' on the cup 71 to limit the upward flexure of the diaphragm. Further, the adjustment of the stop 72 is determined by the angular adjustment of the collar 77 which, in turn, determines which one of the recesses 75 is positioned to engage the locking pin 76. The parts are so proportioned and are of such size that the volume of the mixing chamber is made to correspond to 130 ounces and quarter ounces and any volume may be selected by turning the collar 77 until the appropriate scale marking 81 thereon is aligned with an index marking 82 on the cylinder (see Figure 1).

When the valve 29 is positioned to permit filling of the measuring chamber, in which position the slot 37 bridges the passages 65 and 66, the sirup flows into the measuring chamber under its own head, that is, under the action of gravity.

And the diaphragm 55 freely flexes upwardly since at this time the pressure cylinder 56 immediately above the diaphragm is vented to the atmosphere. In this connection it will be noted that the pressure cylinder 56 connects by a passage 85 in the wall of the cylinder with a passage 86 formed on the measuring chamber 48 and the passage 86 in turn connects with a passage 87 formed in the connecting member 46, having open communication with the pressure chamber 16 above the diaphragm 14. As a consequence, when the cylinder 16 above the diaphragm is vented the pressure cylinder 56 is vented and such venting occurs when the valve 29 is positioned so that its slot 37 bridges the passages 65 and 66 for at such time the slot 38 is necessarily so positioned as to bridge the passage 27 and the vent 39. On the other hand, when the slot 37 is positioned to bridge or connect the passages 66 and 68 and thus connect the measuring chamber with the bottle filling leg 8, the slot 38 bridges or connects the passages 25 and 27 thus supplying pressure to the chamber 16 above the diaphragm 14 and also to the cylinder 56 above the diaphragm 55. The pressure thus supplied to the cylinder 56 forces the diaphragm 55 downwardly and displaces the sirup from the measuring chamber into the bottle.

In Figure 8 a slightly modified form of adjustable slot is shown. As illustrated in this figure the cylinder 56 has a removable cap 90 closing its upper end. Integral with the cap 90 is an internally threaded sleeve or nut 91. The sleeve stop corresponding to stop 72 in the other embodiment of the invention is here designated at 72' and has an external screw thread 93 for a portion of its length, the screw thread 93 intermeshing with the threads of the sleeve 91. The sleeve stop 72' slidably receives the pin 70 of the diaphragm as in the other embodiment of the invention and there is also a stuffing box 74' between the sleeve 91 and the stop 72'. With this form, however, the flanged collar is omitted and the indicia designated at 81' is mounted directly on the stop 72' and coacts with a fixed index mark 82' applied or formed on the sleeve 91.

In operation, the bottles are placed on the holders 2 by an attendant at the loading station in accordance with the usual practice, or they may be placed in any manner on these holders. When the bottles are placed on the holders 2, the latter are lowered but after leaving the loading station the bottle holders are elevated in a manner described in the patent above referred to. When the bottle holders have moved the bottle up into the position shown in Figures 1 and 2 the pins 42 coact with the cams 40 to shift the valve 29 to the position wherein its slots 37 and 38 bridge or connect the passages 25 and 27 and 66 and 68, respectively. As a result, the pressure in the receptacle 1 above the liquid flows into the bottle and also into the chamber 16 above the diaphragm 14 and up into the cylinder 56 above the diaphragm 55. The pressure in the cylinder 56 tends to flex the diaphragm 55 downwardly and consequently to displace the sirup from the measuring chamber down through the passages 67, 66 and through the slots 37 into the passage 68 and thence through passage 10' and tube 8 into the bottle. As soon as the pressure in the chamber 16 rises to a point where it equals the pressure in the receptacle 1, the valve 12 is opened under the

action of gravity and both the sirup and the carbonated liquid flow into the bottle. After the filling operation has been completed the pins 43 coact with the cams 41 to shift the valves 29 back to the position where the pressure supply passage 25 and sirup discharge passage 68 are blocked and wherein the slots 37 and 38 bridge or connect the sirup supply passage 65 and sirup transfer passage 66 and pressure transfer passage 27 and vent 29, respectively. As a consequence, the pressure is bled from the chamber 16 and the cylinder 56 so that the valve 12 closes and the measuring chamber fills with sirup so as to be ready for the next filling operation. After the valves 29 have been shifted in the manner just described, the bottle holders 2 are lowered and the bottles are carried out of the machine at the discharge station in the manner described in the patent above referred to. The amount of sirup delivered to each bottle is determined by adjusting the stops 72 or 72' as the case may be, and thus limiting the extent to which the diaphragm 55 may flex upwardly.

The invention claimed is:

1. A siruping attachment for a filling head of a counter pressure bottle filling machine of the type having means for supplying gas under pressure to the bottle and means for filling the bottle with a carbonated liquid against the counter gas pressure therein, said siruping attachment including a sirup measuring chamber adapted to be connected to a sirup supply, or to the means of the filling head which supplies liquid to the bottle, valve means for establishing communication between said measuring chamber and said sirup supply and for cutting off communication between said measuring chamber and said bottle filling means in one position and also operable in another position to establish communication between the measuring chamber and the bottle filling means while shutting off communication between the measuring chamber and the sirup supply, said measuring chamber having pressure responsive means associated therewith, and connections between the gas pressure supply means of the filling head and said pressure responsive means whereby, as gas pressure is supplied to the bottle, it is also supplied to and acts on said pressure responsive means to move the same and displace the sirup from the measuring chamber to the bottle.

2. A bottle filling machine including a filling head having a valve controlled tube for supplying liquid to the bottle and means of supplying gas under pressure to the bottle, a siruping attachment for the filling head including a source of sirup supply, a sirup measuring chamber having an inlet and discharge passage, said filling head having a sirup feeding passage leading to the bottle filling tube, a diaphragm associated with the sirup measuring chamber and flexible to vary the volume of said chamber, a pressure chamber completing the enclosure of said diaphragm, a connection between the pressure supply means of the filling head and the pressure chamber, valve means controlling the supply of sirup to the measuring chamber and the discharge of the sirup from the measuring chamber to the filling tube and also controlling the supply and exhaust of pressure to the pressure chamber, an adjustable stop engageable with the diaphragm to limit its upward flexure and thereby determine the amount of sirup received in and displaced from the measuring chamber, a fixed guide in which the adjustable stop is slidably and rotatably fit-

- ted, said adjustable stop having a plurality of recesses along its periphery, a manually releasable spring projected detent selectively engageable with said recesses for holding the stop in adjusted position.
3. In a bottle filling machine including a filling head having a valve controlled tube for supplying liquid to the bottle and means of supplying gas under pressure to the bottle, a siruping attachment for the filling head including a source of sirup supply, a sirup measuring chamber having an inlet and discharge passage, said filling head having a sirup feeding passage leading to the bottle filling tube, a diaphragm associated with the sirup measuring chamber and flexible to vary the volume of said chamber, a pressure chamber completing the enclosure of said diaphragm, a connection between the pressure supply means of the filling head and the pressure chamber, valve means controlling the supply of sirup to the measuring chamber and the discharge of the sirup from the measuring chamber to the filling tube and also controlling the supply and exhaust of pressure to the pressure chamber, an adjustable stop engageable with the diaphragm to limit its upward flexure and thereby determine the amount of sirup received in and displaced from the measuring chamber, a fixed guide in which the adjustable stop is slidably and rotatably fitted, said adjustable stop having a plurality of recesses arranged spirally along its periphery, a manually releasable spring projected detent selectively engageable with said recesses for holding the stop in adjusted position,
- 35 an adjusting collar interengaged with the stop to constrain the stop to turn therewith while leaving the stop free to slide therethrough, and cooperating scale markings facilitating accurate adjustment of said adjusting collar.
- 40 4. In a bottle filling machine including a filling head having a valve controlled tube for supplying liquid to the bottle and means of supplying gas under pressure to the bottle, a siruping attachment for the filling head including a source of sirup supply, a sirup measuring chamber having an inlet and discharge passage, said filling head having a sirup feeding passage leading to the bottle filling tube, a diaphragm associated with the sirup measuring chamber and flexible to vary the volume of said chamber, a pressure chamber completing the enclosure of said diaphragm, a connection between the pressure supply means of the filling head and the pressure chamber, valve means controlling the supply of sirup to the measuring chamber and the discharge of the sirup from the measuring chamber to the filling tube and also controlling the supply and exhaust of pressure to the pressure chamber, an adjustable stop engageable with the diaphragm to limit its upward flexure and thereby determine the amount of sirup received in and displaced from the measuring chamber, a fixed guide in which the adjustable stop is slidably and rotatably fitted, said adjustable stop having a plurality of recesses arranged spirally along its periphery, a manually releasable spring projected detent selectively engageable with said recesses for holding the stop in adjustable position, an adjusting collar interengaged with the stop to constrain the stop to turn therewith while leaving the stop free to slide therethrough.
- 45 5. A bottle filling machine comprising a closed liquid receptacle, means for maintaining liquid under pressure at a substantially constant level in said receptacle, a filling head carried by said receptacle and having a filling siphon supplied with liquid under pressure from said receptacle and having a bottle filling leg carrying a bottle sealing cap, a liquid control valve regulating the discharge of liquid through said bottle filling leg, a pressure responsive member connected to said valve and subjected on one side to the action of the liquid under pressure, said filling head having a gas pressure passage leading from the space within the receptacle above the liquid level to the interior of the bottle cap, said pressure passage having a branch leading to the other side of said pressure responsive member, a sirup measuring chamber supported on the filling head and having an inlet and discharge passage connected therewith, said filling head having a sirup supply passage therein and also having a sirup discharge passage leading to the bottle filling leg, a diaphragm in the measuring chamber, a pressure chamber for said diaphragm, a connection between the pressure chamber and the branch of the pressure passage, and valve means mounted on the filling head and controlling the flow of pressure and the flow of the sirup.
- 50 6. A bottle filling machine comprising a closed liquid receptacle, means for maintaining liquid under pressure at a substantially constant level in said receptacle, a filling head carried by said receptacle and having a filling siphon supplied with liquid under pressure from the receptacle and including a bottle filling leg carrying a bottle filling sealing cap, a gas pressure controlled liquid valve regulating the liquid flow through said bottle filling leg, said filling head having a valve seat and being provided with a pressure supply passage leading from the interior of the receptacle to the valve seat, a pressure transfer passage leading from the valve seat to the interior of the bottle sealing cap, a branch passage leading from said pressure transfer passage to the pressure controlling means of said liquid control valve, a sirup measuring chamber mounted on said filling head and having a combined inlet and discharge passage leading to said valve seat, said filling head having a vent leading from the valve seat to the atmosphere and also having a sirup delivering passage leading from the valve seat to the bottle filling tube, a diaphragm in the measuring chamber operable to displace the sirup therefrom, a pressure chamber for said diaphragm, a connection between said pressure chamber and the branch of the pressure passage and a disc valve supported for oscillation on the filling head and in engagement with the valve seat thereof, and having spaced arcuate slots adapted in one position to connect the sirup supply passage to the combined inlet and discharge passage and the pressure transfer passage to the vent while blocking the sirup delivery passage and the pressure supply passage and in its other position to block the vent and the sirup supply passage while connecting the pressure supply passage with the pressure transfer passage and the combined inlet and discharge passage with the sirup delivery passage.
- 55 7. A bottle filling machine comprising a closed liquid receptacle supported for rotation, means for maintaining liquid under pressure at a substantially constant level in said receptacle, a filling head carried by said receptacle and having a filling siphon supplied with liquid under pressure from the receptacle and including a bottle filling leg carrying a bottle filling sealing cap, a gas pressure controlled liquid valve regu-

lating the liquid flow through said bottle filling leg, said filling head having a valve seat and being provided with a pressure supply passage leading from the interior of the receptacle to the valve seat, a pressure transfer passage leading from the valve seat to the interior of the bottle sealing cap, a branch passage leading from said pressure transfer passage to the pressure controlling means of said liquid control valve, a sirup measuring chamber mounted on said filling head and having a combined inlet and discharge passage leading to said valve seat, said filling head having a vent leading from the valve seat to the atmosphere and also having a sirup delivering passage leading from the valve seat to the bottle filling tube, a diaphragm in the measuring chamber operable to displace the sirup therefrom, a pressure chamber for said diaphragm, a connection between said pressure chamber and the branch of the pressure passage and a disc valve supported for oscillation on the filling head and in engagement with the valve seat thereof, and having spaced arcuate slots adapted in one position to connect the sirup supply passage to the combined inlet and discharge passage and the pressure transfer passage to the vent while blocking the sirup delivery passage and the pressure supply passage and in its other position to block the vent and the sirup supply passage while connecting the pressure supply passage with the pressure transfer passage and the combined inlet and discharge passage with the sirup delivery passage, and means controlled by the rotation of the receptacle for automatically shifting said valve.

8. A bottle filling machine comprising a closed liquid receptacle supported for rotation, means for maintaining liquid under pressure at a substantially constant level in said receptacle, a filling head carried by said receptacle and having a filling siphon including a long bottle filling leg carrying a bottle filling cap and a short leg immersed in the liquid in said receptacle, a liquid controlling valve regulating the discharge of liquid through said bottle filling leg, a diaphragm connected to said valve and subjected on one side to the action of the liquid under pressure, said filling head having a pressure passage leading from the space within the receptacle above the liquid level to the interior of the bottle cap, said pressure passage having a branch leading to the other side of said diaphragm, said filling head having a vent leading to the atmosphere, a valve controlling the pressure passage and the vent, and operating in one position to shut off the flow of pressure to the interior of the bottle cap and to

connect the vent to the pressure side of the diaphragm and operating in its other position to block the vent and to permit the pressure to flow to the interior of the bottle cap, and to the gas pressure side of the diaphragm, and means controlled by the rotation of the receptacle of automatically shifting said valve from one position to the other.

9. A siruping attachment for the filling head of a counter-pressure bottle filling machine of the type having means for supplying gas under pressure to the bottle and means for filling the bottle with a carbonated liquid against the counter-pressure therein, said siruping attachment including a sirup measuring chamber adapted to be connected to a sirup supply or to the means of the filling head which supplies liquid to the bottle, means cooperable with said measuring chamber for expelling the sirup therefrom and a single valve acting in one position to provide for the flow of gas under pressure to the bottle and to establish communication between the sirup measuring chamber and the bottle filling means and also operable in another position to shut off the supply of gas under pressure to the bottle and to establish communication between the sirup measuring chamber and the source of sirup supply while shutting off communication between the sirup measuring chamber and the bottle filling means.

10. A siruping attachment for the filling head of a counter pressure bottle filling machine of the type having means for supplying gas under pressure to the bottle and means for filling the bottle with a carbonated liquid against the counter gas pressure therein, said siruping attachment including a sirup measuring chamber adapted to be connected to a sirup supply or to the means of the filling head which supplies liquid to the bottle, pressure responsive means cooperable with said measuring chamber for expelling the sirup therefrom, connections between the gas pressure supply means of the filling head and said pressure responsive means, and a single valve acting in one position to provide for the flow of gas under pressure to the bottle and to establish communication between the sirup measuring chamber and the bottle filling means and also operable in another position to shut off the supply of gas under pressure to the bottle and to establish communication between the sirup measuring chamber and the source of sirup supply while shutting off communication between the sirup measuring chamber and the bottle filling means.

JOHN E. HENES.
